UNITED STATES PATENT OFFICE.

SYDNEY MARTIN, OF MALONE, NEW YORK.

GAME.

Application filed January 27, 1922. Serial No. 532,316.

To all whom it may concern:

Be it known that I, SYDNEY MARTIN, subject of the King of Great Britain, residing at 40 Constable Street, Malone, in the State of New York, one of the United States of America, have invented certain new and useful Improvements in Games; and I do hereby declare that the following is a full, clear, and exact description of the invention, such as will enable others skilled in the art to which it appertains to make and use the same.

This invention relates to improvements in games, having for an object to provide a game of the aero-projectile type, comprehending a game board having means thereon indicative of various numerical values adapted to be rung or similarly engaged by pieces tossed or otherwise projected into engagement with the game board, the ringing of such means requiring dexterity and skill upon part of the players of the game and by consequence, rendering the same both engaging and interesting as an amusement device.

It is also an object of the invention to provide a game employing a novel form of game piece or toss ring, the same being of an elastic or resilient nature whereby when abruptly contacting with the game board, it will have a tendency to rebound therefrom and hence, render the "ringing" of the means on the game board more difficult.

Other objects will be in part obvious and in part pointed out hereinafter.

In order that the invention and its mode of operation may be readily understood by persons skilled in the art, I have in the accompanying illustrative drawings and in the detailed following description based thereon, set out one possible embodiment of the same.

In these drawings:

Figure 1 is a perspective view of the improved game showing the casing thereof closed;

Figure 2 is an elevation of the device when in open position ready for the playing of the game;

Figure 3 is a vertical section therethrough; and,

Figure 4 is a detail in elevation of one of the game pieces employed in the playing of the game.

Having more particular reference to the drawings, in connection with which like

characters of reference will designate corresponding parts throughout, the game may be stated to comprise a casing 1 preferably circular in cross section as shown in the drawing and having a peripherally disposed beading formed upon the upper portion thereof adapted to be engaged by and limit the downward movement of a cover 3 which is hinged to one marginal portion of the casing, as indicated at 4; a spring catch 5 being affixed to an adjacent portion of the casing and adapted to have engagement at its free extremity, with a corresponding portion of the peripheral flange formed upon the circular closure or cover 3.

A lining 6 may be and preferably is provided the interior of the casing 1, being preferably formed of leather or similar material possessing such resiliency or cushioning qualities as will deaden the noise created with the falling of the game pieces hereinafter more fully described, thereinto when projected onto the inner side of the circular cover 3, during playing of the game as well as affording an ornamental finish for the device.

An anchoring base of size and shape corresponding to that of the cover 3 and indicated by the numeral 7 is arranged adjacent the inner side of said cover and preferably, is joined thereto by an adhesive or similar means, said base carrying thereon in spaced relation, a plurality of angularly bent arms 8, the base portions of which are formed to provide fingers which are embedded in the base 7, while the free portions of said arms extend laterally from the inner side of said base and are then bent at substantially right angles to the same and provided with circular enlargements 9, the purpose of which will be hereinafter described. A plurality of these angular arms 8, which are preferably formed of sheet metal possessing a limited degree of pliability are arranged in circular fashion with respect to the base 7, while concentrically thereof, there is arranged another arm 8' having a circular enlargement 9' formed upon its free portion, but of a size greater than the size of the enlargements 9 on the aforesaid arms 8.

Numerals or other matter indicative of values designated by the numeral 10 throughout are presented upon the outer or exposed faces of the enlargements 9 and 9' of the various angularly bent arms, for example, ranging from 50 to 300 upon the arms

8 having the enlargements 9 thereon, while the arm 8' has the numeral 500 or other value indicative indicia arranged thereon, together with the term "Ring" which is arranged directly above the same upon the enlargement 9'.

Game pieces consisting of circularly formed coiled springs indicated by the numeral 11 are employed in the playing of the game and are adapted to be tossed or otherwise projected into engagement with the inner side or face of the base 7 carried by the cover 3, the object being to engage said game pieces with the free portions of the angularly bent arms 8 and 8', preferably, the latter, which, as will be noted, is indicative of the highest numerical value upon the game board. In this connection, it may be here noted that because of the relative size of the enlargement 9' upon the angularly bent arm 8', engagement of the circular game pieces or toss rings 11 thereover is rendered more difficult than is their engagement with the remaining and smaller circular enlargement 9 upon the respective arms 8. Hence, the securing of the highest score possible with the "ringing" of a single arm, namely, the arm 8' is rendered difficult and by consequence adds to the engaging and interesting qualities of the amusement device.

Due to the fact that the toss rings 11 are of an elastic or resilient nature, it will be also understood that their engagement with any of the enlarged portions upon the arms 8 and 8' will be rendered more difficult, since said rings when abruptly contacting with the base 7, will have a tendency to rebound therefrom out of engagement with the same thus requiring considerable dexterity and skill upon part of the players.

In order that the game device may be conveniently carried, I may and preferably do secure a handle 12 thereto through the medium of rivets or similar fastening devices 13 passed through the eyelet spaced opposite extremities of the same into engagement with the base portions of the peripheral flange of the casing 1, while to indicate the nature of the device, it is also preferable that a representation of the arm 8' together with the circular enlargement 9' be arranged upon the outer face of said cover 3 as indicated at 14, a toss ring indicated at 15 being likewise represented thereupon as having engagement with the representation 14.

It is believed that from the foregoing, a clear understanding will be had of the manner in which the game is played, although it will suffice to state herein that in playing the game the cover 3 is swung upwardly to a position at substantially right angles with relation to the casing 1, as shown in the Figure 2, whereupon the various toss rings are

tossed or otherwise projected into engagement with the inner side of the base 7, the object being to engage the various angularly bent arms projecting therefrom, preferably the arm 8' which is indicative of the highest value obtainable in the playing of the game. Any score may be set in the playing of the game and when the particular player has secured this score through the successive "ringing" of the various arms hereinbefore referred to, he, of course, will have won the particular play.

The game, when not in use may be placed in an exceedingly compact form in that it may be packed for shipping or other purposes or may be conveniently carried or placed in some suitable or out of the way place or compartment. Also, by reason of the arrangement of the casing with its cover 3, a receptacle is provided for receiving and retaining the various ring features 11, of which various numbers may be employed, although I have preferably used in connection with this particular embodiment, four of the same.

Manifestly, the construction shown is capable of considerable modification and such modification as is within the scope of my claims, I consider within the spirit of my invention.

I claim:

1. A game comprising a casing, a hinged cover therefor adapted to be moved to substantially right angles with relation to said casing, arms connected to one side of the cover and extending outwardly therefrom, and game pieces adapted to be projected into engagement with said arms, said pieces consisting of circular coil springs.

2. A game comprising a base, arms connected to one side thereof extending outwardly therefrom and having angularly disposed enlargements formed at their free ends, and game pieces adapted to be projected into engagement with said arms, said pieces consisting of circular coil springs.

3. A game comprising a base, a circular series of arms extending outwardly from one side thereof and having enlargements at their free ends, an additional arm in the centre of said series, said last named arm having an enlargement of greater dimensions than the aforementioned enlargements, and resilient rings adapted to be projected into engagement with said arms.

4. A game comprising a casing, a hinged cover therefor adapted to be moved to substantially right angles with relation to said casing, arms connected to one side of the cover extending laterally therefrom and having angularly disposed enlargements formed on their free portions and game pieces adapted to be projected into engagement with said arms consisting of circular coiled springs.

5. A game comprising a casing, a hinged cover therefor adapted to be moved to substantially right angles with relation to said casing, arms connected at their outer ends to said cover and extending laterally therefrom, having circularly formed enlargements upon their free portions and disposed at angles, said enlargements varying in size

and having indicative matter representative of certain values thereon, and game pieces 10 adapted to be projected into engagement with said arms comprising circular coiled springs.

In witness whereof I have hereunto set my hand.

SYDNEY MARTIN.
